(57) **CLAIM**

The ornamental design for an ultrathin absorbent asymmetrical bladder liner, as shown and described.

DESCRIPTION

FIG. 1 is a top perspective view of the ultrathin absorbent asymmetrical bladder liner, as seen from the top, front, and side;

FIG. 2 is a top plan view thereof;

FIG. 3 is a bottom plan view thereof;

FIG. 4 is a right side elevation view thereof;

FIG. 5 is a left side elevation view thereof;

FIG. 6 is a rear elevation view thereof; and,

FIG. 7 is a front elevation view thereof.

The broken line depiction of an ultrathin absorbent asymmetrical bladder liner is included for the purpose of illustrating environmental structure and forms no part of the claimed design.
